HAIRCOMB

Irene M. Dorr, 103 Oakway Road, Timonium, Md.

Filed June 29, 1959, Ser. No. 56,571

Term of patent 14 years

(Cl. D86—8)

FIG. 1

FIG. 2

FIG. 3

FIG. 4

Fig. 1 is a side elevation of a haircomb showing my new design;

Fig. 2 is a side elevation of the opposite side of the haircomb of Fig. 1;

Fig. 3 is a top plan view of the haircomb shown in Fig. 2; and

Fig. 4 is a cross section taken along line 4—4 of Fig. 3.

I claim:

The ornamental design for a haircomb, as shown.
